UNITED STATES PATENT OFFICE.

LEON BRAULT, OF WAUSAUKEE, WISCONSIN.

SHINGLE-SAWING MACHINE.

SPECIFICATION forming part of Letters Patent No. 779,260, dated January 3, 1905.

Application filed April 11, 1904. Serial No. 202,673.

To all whom it may concern:

Be it known that I, LEON BRAULT, a citizen of the United States, residing at Wausaukeee, in the county of Marinette and State of Wisconsin, have invented new and useful Improvements in Shingle-Sawing Machines, of which the following is a specification.

My invention relates to a spalt-ejector for shingle-sawing machines; and the object of my invention is to provide a ready means of ejecting the spalt without stopping the machine.

In the accompanying drawings, Figure 1 is a plan view, Fig. 2 a side view, and Fig. 3 an end view, of my invention.

A represents the frame, B the tip-table, and C the saw, of a shingle-sawing machine.

D represents the sliding dog, and E represents the stationary dog.

F represents the carriage, and G one of the carriage-tracks.

The dogs grip the shingle-block, the carriage carries it forward upon the saw, then back over the tip-table. The dogs then release the block, and the tip-table operates to tilt the block in the opposite direction before it is again gripped by the dogs and carried forward. The operator stands at the side of the track G and usually feeds the block when the carriage is forward over the saw. The drawings illustrate an automatic power-feed machine. In describing my invention it will be considered that the carriage moves forward upon the saw and rearward in returning. Fig. 3 will therefore be considered a view of the rear end of the machine.

The object of my invention is to eject the spalt from the rear end of the machine, so that in the next forward movement of the carriage a new block may be fed upon the saw.

H represents a gate sliding vertically in ways I I at the rear of the carriage and operated by the crank-arms J J, which are keyed to the shaft K. The shaft K is properly journaled in journal-boxes k k k, mounted on the carriage, and carries the crank-arm L, provided with an outwardly-extending traveler l, which travels just above the track G.

M represents an incline-plate controlled and

operated by the handle N. The handle N is 50 keyed to the revoluble shaft O and is of sufficient weight to normally hold the plate M at the dotted position M', Fig. 3, out of action. The gate H normally forms the rear bearing of the entire shingle-block as it is forced 55 against the saw. When the operator desires to eject a spalt, he raises the handle from the position N' to the position N, Fig. 3. The incline-plate M will then be at the position shown in Figs. 1 and 2 upon the track G. As 60 the carriage returns rearward the traveler l travels up the incline M, thereby revolving the shaft K rearward and also revolving the crank-arms J J. Each crank-arm J is provided with jaws j j, which engage a pin h, attached to the gate H, and afford enough reciprocation so that the upward revolution of the crank-arm J raises the gate perpendicularly. The gate is raised while the carriage is returning rearward, and the momentum of the 70 spalt is sufficient when the carriage stops to throw it back beneath the gate off from the tip-table. If this does not occur, the gate may be dropped in front of the spalt at the next forward movement of the carriage, a new 75 block fed to the machine over the saw, and upon the next return of the carriage the closed gate will push the spalt rearward from the tip-table. The operator holds the handle N up until the spalt is ejected, then releases the 80 handle, when its weight will revolve the shaft O and carry the incline-plate M to the position M' out of action. The shaft O is suitably journaled to the frame at o o, and the plate M may be set at any position longitudinally 85 of the shaft by means of the set-screw m.

The gate drops by gravity; but to prevent clogging or sticking on the ways a central spring P is provided. When the gate is raised, it compresses the spring, which pushes downwardly the moment the gate is released.

Q represents a spring-hub keyed to the shaft K and carrying the spring S. When the handle N is raised, the revolution of the shaft brings the spring down, so that its point S 95 springs against the bracket R upon the rear end of the sliding dog D. When the dog spreads to release the spalt, the end S springs

down just below the top of the bracket R, engages the inner edge of the bracket, and holds the dog open, so that it cannot grip the spalt while being ejected. When the handle N is 5 dropped, the spring S is raised out of action.

Having now described my invention, what I claim as new, and desire to secure by Letters Patent, is—

1. In a shingle-machine, a traveling frame, 10 gripping means thereon; a removable backing means for the block, and means for lifting the same out of position for discharging spalts.
2. In a shingle-machine, the combination with a suitable frame, of means for forcing a 15 block against a cutting device comprising a traveling frame and a vertically-moving gate carried thereby, the said gate normally forcing the shingle-block against the cutting means, and means for shifting the gate to permit the discharge of spalts.
3. In a shingle-machine, the combination with a suitable frame, a sliding member mounted thereon, a vertical-moving gate for forcing the shingle-block forwardly in the machine, 20 means for raising or lowering the gate, and hand-operated means capable of being brought into position to operate said gate.
4. In a shingle-sawing machine, the combination of a frame, a sliding block-carrying 25 member mounted thereon, a tip-table mounted adjacent thereto, a vertically-movable gate carried by the moving member, and a rock-shaft for operating the said gate.
5. In a shingle-sawing machine, a frame, a 30 block-handling mechanism movably mounted therein comprising a table, grippers for holding the said block, and a gate for forcing the block forward, pivotally-mounted arms engaging the said gate, a shaft carrying said 35 arms and a trip mechanism for rocking the shaft and shifting the gate at the proper time for discharging spalts from the machine.
6. A shingle-sawing machine comprising a frame, a block-carrying mechanism mounted 40 therein, a block-engaging gate movably mounted upon said carrying mechanism, a rock-shaft connected with the said gate, and a trip mechanism capable of movement into and out of engagement with the said shaft, the 45 gate being lifted for discharging spalts from the machine when the tripping mechanism is brought into engagement with the shaft.
7. A block-controlling mechanism for shingle-sawing machines comprising a tip-table, a 50 movable frame above the table, grippers, an abutment-gate mounted adjacent thereto, and means for lifting the abutment-gate to per-

mit of the ejection of spalts at the rear of the machine.

8. In a shingle-sawing machine, means for 60 carrying shingle-blocks forward against a cutting device, comprising a sliding frame, a tip-table for supporting the said blocks and an abutment-gate having a sliding engagement with said frame near the rear end thereof, a 65 rock-shaft for lifting the said gate, and a removable wedge-block or inclined plane for tripping the said rock-shaft, and lifting the abutment-gate from behind the spalts permitting of their ejection at the rear of the 70 machine.

9. A block-handling mechanism for shingle-sawing machines comprising a sliding frame, a fixed and a movable gripper carried by the said frame, an abutment-gate at one end of 75 the frame, a rock-shaft for lifting the gate, a spring-arm projecting from said shaft, means for rocking the shaft to lift the abutment-gate, the spring-arm at the same time being moved into the path of the movable dog for 80 holding the same out of engaging position while spalts are ejected beneath the abutment-gate.

10. A block-handling mechanism for shingle-machines comprising a moving frame, 85 grippers carried thereby, an abutment-gate mounted adjacent to the grippers, a rock-shaft for elevating the gate, a spring for forcing the gate downwardly, a crank carried by the said rock-shaft, a movable wedge-block for 90 engaging the said crank and thereby rocking the shaft, and a weighted arm for moving the wedge-block into and out of operative position.

11. A block-handling mechanism for shingle-machines, comprising a sliding frame, grippers thereon, an abutment-gate, a rock-shaft for operating the said gate, a crank-arm carried by said shaft, a wedge-block capable of movement into and out of engagement with 100 said crank-arm, a shaft carrying the said wedge-block, bearings carrying said shaft, and means for adjustably securing the wedge-block at suitable points upon said shaft, the block being moved into and out of operative 105 position upon rocking the said shaft.

In testimony whereof I have hereunto set my hand in the presence of two subscribing witnesses.

LEON BRAULT.
